UNITED STATES PATENT OFFICE.

LUTHER E. SHINN, OF PITTSBURG, PENNSYLVANIA.

MIXING DEVICE.

SPECIFICATION forming part of Letters Patent No. 732,661, dated June 30, 1903.

Application filed October 23, 1902. Serial No. 128,512. (No model.)

To all whom it may concern:

Be it known that I, LUTHER E. SHINN, a citizen of the United States, residing at Pittsburgh, in the county of Allegheny and State of Pennsylvania, have invented certain new and useful Improvements in Mixing Devices, of which the following is a full, clear, and exact specification.

This invention relates to mixing devices, and has special reference to such devices used for the purpose of mixing or beating eggs, cream, &c. Its object is to provide a device of this character which shall be of simple and economical manufacture, easily manipulated, and wherein the mixture will be contained in one receptacle and prevented, as far as possible, from adhering to the cover or walls in such manner as to interfere with the thorough mixture of the material.

The invention also comprehends other features of advantage, which will be referred to more in detail hereinafter.

In the drawings, in which I have illustrated forms which the invention may take in practice, Figure 1 is a front view of a mixer embodying my invention. Fig. 2 is a side view of the same.

Referring more particularly to the drawings, 1 represents a suitable receptacle, the bottom of which in this instance tapers to an egg-shaped bowl. The receptacle is supported upon a base 2 and is provided with a cover 3, adapted to be conveniently fitted to the top of the receptacle. In the cover 3 is mounted a central shaft 4, upon the end of which, below the cover, one or more beaters 5 6 are mounted. These beaters are shown as comprising loops of wire, the ends of which are sprung into holes in the end of shaft 4 or otherwise separably attached, and which are bent alternately outward and inward to form horizontal arms, the lower end being shaped to conform to the bottom of the receptacle. Where two or more beaters are employed, they are preferably located in planes at angles to each other, as shown, and so formed that the arms of the several beaters are staggered with respect to each other—that is, the arms of one beater are located opposite the space between the arms of the other beater. The lower end of each beater is in the form of a double loop and has a notch or offset 11 at

about the center thereof, (see Figs. 1 and 2,) so that when the beaters are put together the notches hold the lower ends in engagement with each other. By this construction the beaters can be easily separated from the shaft and from each other for packing or cleaning and do not get out of alinement. Preferably, also, the inner bends of the wires of the several beaters are separated from each other. Upon the cover 3 is carried suitable means for revolving shaft 4, such as the crank 7, connected with shaft 4 by wheel 8 and pinion 9, mounted on shaft 4.

In operation the material to be mixed or beaten is placed in the receptacle and the cover placed thereon. As the cover carries shaft 4, the beaters, and the gearing and crank for revolving the beaters, the simple act of placing the cover upon the receptacle will insert the beaters in the mixture and in all respects make the device ready for operation. Whether the material be enough to fill the receptacle or not it will not be splashed upon the cover or caught in corners of the receptacle and thus not mixed, because owing to the horizontal motion of the beaters there will be no tendency to splash upon the cover, and owing to the tapering egg-shaped bottom 80 all the material will gravitate to the bottom and be mixed by the beaters, which conform to the shape of the bottom.

It will be seen that the device above described may be modified in various respects 85 without departing from the invention, and I therefore desire it to be understood that I do not herein limit myself to the specific construction shown.

Having thus described my invention, what 90 I claim as new, and desire to secure by Letters Patent, is—

1. In a mixer the combination of a receptacle having an egg-shaped bottom, a cover therefor, a plurality of beaters each of which 95 comprises a loop of wire bent alternately outward and inward to form horizontal arms and its lower end conforming in shape to the bottom of the receptacle, said beaters being located in different vertical planes and separably engaging each other at the bottom and the arms of the several beaters being staggered, a shaft mounted in said cover and carrying said beaters, separably, on its lower end,

and means, carried by said cover, for rotating said shaft.

2. In a mixer, the combination of a receptacle having a curved bottom, a cover carrying a shaft projecting into the receptacle, the end of the shaft having transverse holes at angles to each other, beaters, each composed of a flat loop of wire bent outwardly, downwardly and inwardly to form single arms on the sides and a double arm on the bottom conforming in contour to the receptacle, the

ends of the loop being sprung into the holes in the shaft, the respective arms of the beaters being staggered, and means carried on the cover for rotating the shaft.

In testimony whereof I affix my signature in presence of two witnesses.

LUTHER E. SHINN.
